UNITED STATES PATENT OFFICE.

DAVID C. PRINCE, OF SCHENECTADY, NEW YORK, ASSIGNOR TO GENERAL ELECTRIC COMPANY, A CORPORATION OF NEW YORK.

VACUUM-TUBE CIRCUITS.

Application filed May 4, 1923, Serial No. 636,896. Renewed November 30, 1927.

My present invention relates to vacuum tube circuits and more particularly to circuits employed with vacuum tubes for producing alternating currents from direct currents.

My present application is a continuation in part of my prior application Serial No. 599,919, filed November 9, 1922.

One of the objects of my invention is to provide a simple and efficient circuit connection for converting direct current to alternating current by means of vacuum tubes having asymmetric current conducting properties.

A further object of my invention is to provide means whereby the operation of the vacuum tubes may be controlled in such a way that the periods during which individual devices are in operation will vary in a desired manner in accordance with variations in the load supplied by the system.

The novel features which I believe to be characteristic of my invention are set forth with particularity in the appended claims.

My invention itself, however, both as to its organization and method of operation will best be understood by reference to the following description taken in connection with the accompanying drawings in which Figs. 1 to 4, inclusive, show diagrammatically as many different circuit arrangements whereby my invention may be carried into effect and Fig. 5 is a representation of the relation between the currents in different tubes under varying load conditions.

In the arrangement shown in Fig. 1 three vacuum tubes or valves 1, 2 and 3, are indicated with connections for converting direct current to three-phase alternating current. These tubes are indicated as being of the three electrode thermionic type but my invention is not limited to use with tubes of this type as it may be carried out by means of other forms of asymmetric devices which are provided with means for controlling the flow of current in a desired manner. The plate circuits of valves 1, 2 and 3 include windings 4, 5 and 6 and choke inductance 7 through which current is supplied from the direct current source 8. The windings 4, 5 and 6 are connected in Y and inductively related to the delta connected secondary windings 9, 10 and 11, which supply three-phase alternating current to a load which may be connected to the supply conductors 12, 13 and 14. The

load itself may form the frequency determining element or separate frequency determining apparatus may be connected to the supply conductors. The grid potentials required for controlling the operation of valves 1, 2 and 3 may be supplied by means of primary windings 15, 16, 17 and secondary windings 18, 19, 20 arranged similarly to windings 4, 5, 6 and 9, 10, 11. The individual grids are fed through ballast resistances 21, 22 and 23. The neutral points of windings 18, 19 and 20 are connected to the negative terminal of source 8 through resistance 24 and inductance 25. Windings 15, 16 and 17 are fed from 9, 10 and 11 by variable taps 26, 27 and 28 in such a way that the phase of the grid control potentials may be varied for purposes which will be hereinafter explained.

In order to explain the operation of the system described assume that the frequency determining element or load connected to the supply conductors 12, 13 and 14 is in operation and is generating sine waves of counter electromotive force. This counter electromotive force is induced in the inductances 4, 5 and 6 and thereby applied to the anodes of valves 1, 2 and 3. Inductance 7 will maintain substantially constant current through the valves so that when current is flowing through one valve only, as will be the case during the greater portion of the time, the impressed potential must be higher than the counter-electromotive force by an amount sufficient to overcome the counter electromotive force and cause current to flow.

Referring now to Fig. 5, assume that current I_1 is flowing through valve 1 and that at time t the grid of valve 2 is made positive so that current can flow in valve 2. Valves 1 and 2 are then fully conducting and there is a difference in the voltage applied to the two valves which is available to start a transfer of current from one to the other. Since the total current is maintained constant by reactance 7, current can flow in valve 2 only at the expense of valve 1. However, if the current in valve 1 has not been reduced to zero by time t_1 at which it is assumed that the voltages of the two phases are equal the difference voltage reverses and current tends to return to valve 1. If the grid of valve 1 is made negative under these conditions at time t_1 the valve must absorb the inductive energy represented by the leakage flux in both phases corresponding to the residual current. If the

grid is made negative at a still later point not only will the current through valve 1 be larger but there will also be a voltage difference to be overcome.

- 5 In order that the current shall be transferred properly from valve 1 to valve 2 it must come to zero in valve 1 at the instant the phase difference voltage is equal to the resistance drop in phase 2, as for example, 10 at a time t_2 . If a negative potential is impressed upon the grid of valve 1 at this point there will be no loss to absorb in the valve and no inductive surges in any of the windings.

The flow of current in valve 1 is automatically reduced in the manner indicated by reason of the fact that at the time valve 2 is made conducting the counter electromotive force applied to the anode is greater than the impressed potential and this difference is 20 available to stop the flow of current in the valve.

In order that one valve may be made conducting before the preceding valve becomes non-conducting the potentials applied to the 25 grids of the valves in each phase should lead the potentials in the supply circuit. This effect is secured by means of the taps 26, 27 and 28 in the arrangement shown in Fig. 1. The current in the grid circuits is maintained 30 constant by the inductance 25 and the grid current is transferred from one valve to the succeeding one in much the same manner that the plate currents are transferred.

From an inspection of the families of 35 curves of Fig. 5 which represent currents through the valves for different load conditions it is apparent that the lead angle, that is the angle by which the grid excitation should lead the plate potential varies with 40 the load and that the time of overlap during which current flows in both valves also varies with the load. It is therefore desirable, although not necessary that these values should vary with the load. By adjustment of the 45 taps 26, 27 and 28 the lead angle can be adjusted for any given load but will not vary with the load.

One arrangement whereby this desired result may be brought about is indicated in 50 Fig. 2. In this case series inductances 29, 30 and 31 are connected to the supply conductors 12, 13 and 14, the terminals of the transformer windings 9, 10 and 11 being connected by variable connections 32 to points 55 in these inductances intermediate the ends. The transformer windings 15, 16 and 17 are connected to the inductances 29, 30 and 31 by variable connections 33. When the load increases both the amplitude and angle of lead 60 of the potentials impressed from transformer windings 15, 16 and 17 upon the grid circuits of the valves increase, and as a result the lap and lead of the conducting periods of the valves are automatically increased as desired. 65 By suitable adjustment of the connection 32

and 33 the lap and lead may be given the desired values over a wide range of load.

In the arrangement shown in Fig. 3, each of the inductances 29, 30 and 31 forms the primary winding of a transformer having 70 two secondary windings 34 to 39 inclusive. Two of these secondary windings which are supplied from different primaries are connected in series with each of the conductors 40, 41 and 42 connecting windings 9, 10 and 75 11, to the windings 15, 16 and 17. By suitable choice of the number of turns in the secondaries 34 to 39 the desired variation in amplitude and lead angle with variations in load may be obtained. 80

In the system shown in Fig. 4, separate primary windings 43, 44 and 45 are provided for the grid transformer and inductances 46, 47 and 48 are connected in series with these windings. The taps 26, 27 and 28 are adjusted to give a lead angle greater than that required and this lead angle is reduced to the proper value by the series inductance. When the load current increases the grid current decreases. As a result the potential drop across the inductances 46, 47 and 48 decreases and the angle of lead of the potentials applied to the grids automatically increases. 90

While I have shown and described the preferred embodiments of my invention it is apparent that my invention is not limited to the particular embodiment set forth as many modifications in the form of apparatus as well as in the circuit connection used therewith may be made without departing from the 100 scope of my invention as set forth in the appended claims. 95

What I claim as new and desire to secure by Letters Patent of the United States is—

1. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, and means for impressing upon the control circuit of each valve a control potential which leads the potential 110 of the corresponding plate circuit secondary winding. 115

2. The combination in a system of electrical distribution of a plurality of electron discharge valves having plate and control 120 circuits, a source of direct current connected to the plate circuits of said valves, each of the plate circuits of said valves including a primary winding of a transformer, secondary transformer windings associated with 125 said primary windings, a secondary transformer winding included in each of said control circuits, and means for impressing upon each of the secondary windings included in said control circuit a potential which leads 130

the potential of the corresponding plate circuit secondary winding.

3. The combination in a system of electrical distribution of a plurality of electron discharge valves having plate and control circuits, a source of direct current connected to the plate circuits of said valves, each of the plate circuits of said valves including a primary winding of a transformer, secondary 50 transformer windings associated with said primary windings, a secondary transformer winding included in each of said control circuits, a primary transformer winding associated with each of said control circuit 55 10 secondary windings and means for impressing upon each of said control circuit primary windings a potential which leads the potential of the corresponding plate circuit secondary winding.

20 4. The combination in a system of electrical distribution of a plurality of electron discharge valves having plate and control circuits, a source of direct current connected to the plate circuits of said valves, each of 50 25 the plate circuits of said valves including a primary winding of a transformer, secondary transformer windings associated with said primary windings, and means for impressing upon the control circuit of each 30 35 valve a control potential which is derived from the plate secondary windings and which leads the potential of the corresponding plate circuit secondary winding.

5. The combination in a system of electrical distribution of a plurality of electron discharge valves having plate and control circuits, a source of direct current connected to the plate circuits of said valves, each of the plate circuits of said valves including 40 a primary winding of a transformer, secondary transformer windings associated with said primary windings, a secondary transformer winding included in each of said control circuits, and means for impressing upon each of the secondary windings included in said control circuit a potential which is derived from the plate secondary windings and which leads the potential of the corresponding plate circuit secondary winding.

50 6. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, a secondary transformer winding included in each of said control circuits, a primary transformer winding associated with each of said control circuit secondary windings, and means for impressing upon each of said control circuit primary windings a potential which is derived from the plate secondary windings and which leads 55 60 65 70 75 80 85 90 95 100 105 110 115 120 125 130

the potential of the corresponding plate circuit secondary winding.

7. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, and means for impressing upon the control circuit of each valve a control potential which leads the potential of the corresponding plate circuit secondary winding, and the angle of lead of which varies with the load supplied by the plate secondary winding.

8. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, a secondary transformer winding included in each of said control circuits, and means for impressing upon each of said secondary windings a potential which leads the potential of the corresponding plate circuit secondary winding, and the angle of lead of which varies with the load supplied by the plate secondary winding.

9. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, a secondary transformer winding included in each of said control circuits, a primary transformer winding associated with each of said control circuit secondary windings, and means for impressing upon each of said control circuit primary windings a potential which leads the potential of the corresponding plate circuit secondary winding and the angle of lead of which varies with the load supplied by the plate secondary winding.

10. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, and means for impressing upon the control circuit of each valve a control potential which is derived from the plate secondary windings, which leads the potential of the corresponding plate circuit

secondary winding, and the angle of lead of which varies with the load supplied by the plate secondary winding.

11. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, a secondary transformer winding included in each of said control circuits, and means for impressing upon each of said secondary windings a potential which is derived from the plate secondary windings, which leads the potential of the corresponding plate circuit secondary winding and the angle of lead of which varies with the load supplied by the plate secondary winding.

12. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, a secondary transformer winding included in each of said control circuits, a primary transformer winding associated with each of said control circuit secondary windings, means for impressing upon each of said control circuit primary windings a potential which is derived from the plate secondary windings, which leads the potential of the corresponding plate circuit secondary winding and the angle of lead of which varies with the load supplied by the plate secondary winding.

13. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, and means for impressing upon the control circuit of each valve a control potential which leads the potential of the corresponding plate circuit secondary winding, and the amplitude of which varies with the load supplied by the plate secondary winding.

14. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, a secondary transformer winding included in each of said control cir-

cuits, and means for impressing upon each of the secondary windings included in said control circuits a potential which leads the potential of the corresponding plate circuit secondary winding and the amplitude of which varies with the load supplied by the plate secondary winding.

15. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, a secondary transformer winding included in each of said control circuits, a primary transformer winding associated with each of said control circuit secondary windings and means for impressing upon each of said control circuit primary windings a potential which leads the potential of the corresponding plate circuit secondary winding and the amplitude of which varies with the load supplied by the plate secondary winding.

16. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, and means for impressing upon the control circuit of each valve a control potential which is derived from the plate secondary windings, which leads the potential of the corresponding plate circuit secondary winding and the amplitude of which varies with the load supplied by the plate secondary winding.

17. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, a secondary transformer winding included in each of said control circuits, and means for impressing upon each of the secondary windings included in said control circuits a potential which is derived from the plate secondary windings, which leads the potential of the corresponding plate circuit secondary winding and the amplitude of which varies with the load supplied by the plate secondary winding.

18. The combination in a system of electrical distribution of a plurality of electron discharge valves having plate and control circuits, a source of direct current connected to the plate circuits of said valves, each of the

- plate circuits of said valves including a primary winding of a transformer, secondary transformer windings associated with said primary windings, a secondary transformer 5 winding included in each of said control circuits, a primary transformer winding associated with each of said control circuit secondary windings, means for impressing upon each of said control circuit primary windings 10 a potential which is derived from the plate secondary windings, which leads the potential of the corresponding plate circuit secondary winding and the amplitude of which varies with the load supplied by the plate secondary 15 winding.
19. The combination in a system of electrical distribution of a plurality of electron discharge valves having plate and control circuits, a source of direct current connected to 20 the plate circuits of said valves, each of the plate circuits of said valves including a primary winding of a transformer, secondary transformer windings associated with said primary windings, means for impressing upon 25 the control circuit of each valve a potential derived from the plate secondary windings, and means for adjusting the phase of the potential impressed upon each control circuit.
20. The combination in a system of electrical distribution of a plurality of electron discharge valves having plate and control circuits, a source of direct current connected to 30 the plate circuits of said valves, each of the plate circuits of said valves including a primary winding of a transformer, secondary transformer windings associated with said primary windings, means for impressing upon 35 the control circuit of each valve a potential derived from the plate secondary windings, and means for adjusting the phase and amplitude of the potential impressed upon each control circuit.
21. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, means for impressing upon the control circuit of each valve a potential derived from the plate secondary windings, and means for adjusting the phase and amplitude of the potential impressed upon each control circuit.
22. The combination in a system of electrical distribution of a plurality of electron discharge valves having plate and control circuits, a source of direct current connected to the plate circuits of said valves, each of the plate circuits of said valves including a primary winding of a transformer, secondary transformer windings associated with said primary windings, means for impressing upon 45 the control circuit of each valve a potential derived from the plate secondary windings, and means for varying the phase of the potential impressed upon each control circuit 50 in accordance with the load supplied by the plate secondary winding.
23. The combination of an electron discharge device provided with a cathode and anode and with a grid arranged to control the current transmitted between said cathode and anode, a transformer comprising a plurality of windings one of which is connected between said cathode and anode, and means connected between another of said windings and 55 said grid for applying to said grid a potential which has its phase varied in accordance with the load of said transformer.

In witness whereof I have hereunto set my hand this 3rd day of May, 1923.

DAVID C. PRINCE.
